UNITED STATES PATENT OFFICE.

LEROY BIGGS, OF CROVILLE, WASHINGTON.

CAN-LABELING MACHINE.

Application filed January 26, 1928. Serial No. 249,681.

This invention relates to can labeling machines and aims, among other objects, to provide an improved machine of the type wherein cans may be continuously fed and allowed 5 to roll, one at a time, longitudinally of the machine, and in which the cans automatically actuate label applying mechanism to paste the label to the can, while the latter is in transit, in a manner to insure the desired 10 adherence of the label, with the minimum amount of paste.

Referring to the drawings, wherein the preferred embodiment of the invention is illustrated:-

15 Fig. 1 is a side elevation of the improved labeling machine.

Fig. 2 is a plan view of the can receiving end of the machine and drawn on a larger scale.

20 Fig. 3 is a view, similar to Fig. 2, of the discharge end thereof.

Fig. 4 is a fragmentary longitudinal sectional view through the intermediate portion of the machine.

25 Fig. 5 is an enlarged side elevation of the discharge end.

Fig. 6 is a longitudinal section through the subject matter of Fig. 5.

Fig. 7 is a view similar to Fig. 6 and showing the movement of the parts.

Fig. 8 is a detail section taken on the line 8-8 of Fig. 4.

Fig. 9 is a section taken on the line 9-9 of Fig. 2, and

35 Fig. 10 is a transverse section of the machine, taken on the line 10-10 of Fig. 6.

Referring to the drawings, there is shown an elongated frame adapted to rest upon a suitable support and comprising spaced side 40 walls or members preferably in the form of suitable castings of open formation and marginally flanged to insure strength. Each side member preferably comprises two sections, 1 and 2, section 1 of each member being

45 higher than section 2 thereof, and constituting the can-receiving end of the machine, while the sections 2 constitute the discharge end thereof. The two sections are held together by suitable fasteners 3 in the form of screws or bolts while spacing blocks 4, together with suitable co-acting bolts hold the spaced, parallel sections 1 in proper relation to each other and similar spacing blocks and bolts 5 hold the sections 2.

55 Mounted on the upper edges of the sections 1, which are generally inclined for the pur-

pose, are spaced track members each having an inwardly-directed flange 6 constituting a rail on which the cans roll downwardly towards the discharge end of the machine, it 60 being understood that the machine is intended for use in applying labels to cans which have been filled and sealed and have sufficient weight to cause them to roll with force enough to actuate the label applying 65 mechanism to be later described.

The track members are connected to each other by spacing blocks or bars 7 held by bolts or otherwise, and the said members have outstanding flanges 8 at their upper 70 ends which are adapted to rest upon supports 9 formed on the upper ends of the sections 1, while similar flanges 10 are formed on the track members, adjacent to their lower ends, and in position to rest upon corresponding supports 11 of the sections 1, to rigidly maintain the track members in inclined position upon the frame.

The sections 1 of the frame are each provided with corresponding drop portions 12 80 for the reception of a transversely-disposed paste receptacle 13 together with a heating element 14 which is preferably of an electrical type. The paste receptacle and heating element are preferably detachable from the 85 machine for the purpose of cleaning the said receptacle and to this end, arms 15 are formed on the upper rear edge of the receptacle, said arms being adapted to rest upon inwardly-directed lugs 16 carried by the 90 track members, while other, angularly-bent arms 17 extend from the upper, front edge of the receptacle and rest upon inwardly-extending lugs 18 which are also formed on the inner faces of the track members. By 95 this arrangement, it will be seen that the paste receptacle and heating element may be easily disengaged from its supported position, by suitably sliding and tilting the same in an obvious manner, when desired.

Upstanding, alined posts 19 are formed on the upper edges of the track members near their upper ends, said posts having suitable apertures for the trunnions 20 of a can-checking arm 21 extending towards the discharge 105 end of the machine and adapted to rest normally in a downwardly-inclined position, as shown in dotted lines in Fig. 1, and to be elevated when engaged by a can C to the full line position shown in said figure.

110 A suitable hopper, incline, or chute (not shown) is adapted to be supported at the up-

per end of the machine from which the cans may roll onto the tracks 6, and when one can has advanced to elevate the arm 21, the next following can is checked and held from further rolling by means of forwardly directed lugs 22 formed on the cross bar of the checking device and inclining downwardly when the finger 21 is elevated, and being elevated when the finger drops, to a position to permit another can to pass, as shown in dotted lines in Fig. 1.

As the can, in rolling, approaches the free end of the finger 21, and the following cans are retarded, a trip lever 23, located centrally of the machine, is encountered and rocked forwardly to rotate a transverse shaft 24 terminally journalled in the sides of the track members. Through the medium of gearing 25, located at one side of the machine, this shaft 24 imparts motion to a second rock shaft 26 also conveniently journalled in the track members and having a plurality of angularly bent paste-applying fingers 27, which normally lie at an inclination within the paste receptacle 13, the ends of the fingers resting upon the bottom thereof. By this arrangement it will be seen that the fingers are elevated when the can contacts with the trip lever 23 and the fingers, having a quantity of paste adhering thereto will each apply paste in a short arcuate path on the can as the latter passes over same. In the present instance, there has been shown three of such fingers which apply the paste on the bare can, two of the applications being made near the ends of the can. As the shaft 26 is thus rocked, crank arms 28 secured to each projecting end thereof are caused to impart a pulling action on connecting rods 29 located on the outer sides of the track members and connected at their other ends to cam levers 30 mounted for horizontal swinging movement upon upstanding posts 31 secured on the outer faces of the front ends of the track members, which are provided with depending end portions 32 having their lower edges located close to the inclined upper edges of the frame sections 2. The cam levers are adapted to bear inwardly against hinged leaves 34 operable within openings 35 formed in the rear edges of the drop portions 32 of the sections 2, said leaves having eyes 36 formed in their outer, forward ends for the reception of pintles journalled in brackets 37 secured to the outer sides of said sections.

When the can C, after having the paste applied thereto, as above described, rolls along the tracks 6 towards the leaves 34, it gathers sufficient momentum to carry same beyond the end 6^a of said tracks and in position to be arrested in its flight by a stop 38 in the form of a bail having its side arms directed forwardly towards the entrance end of the machine and pivoted to the outer sides of the track members, as at 39. The can is thus

caused to fall, substantially in a vertical direction, to contact with the proper edge of the uppermost of a stack of labels L supported in a forwardly inclined position and with said edges substantially midway between the ends 6^a of the tracks and the leaves 34, (see Fig. 4). The distance between the paste applying fingers 27 and the upper front edge of the stack of labels is substantially equal to the circumference of the can, so that as the can falls on the top label, the paste on the can will cause the front end of the label to adhere to the can. In traversing the tracks between the paste receptacle 13 and the ends 6^a of the tracks, the can contacts with a second upstanding trip lever 40 mounted on a rock shaft 41 for the purpose of actuating a second paste applying means to be later described.

The labels L are supported at an inclination by means of a bed or platform 42, located between the sections 2 and having depending ears for the reception of bolts 43 passing through said sections, and said inclination is considerably greater than that of the tracks 44 formed on the inner faces of the sections, so that the can, in contacting with only the end portion of the label, will pick up a single label allowing air to enter below the same to avoid two or more adhering to the can, and then roll free from the stack of labels, along the tracks 44 of lesser inclination, after being momentarily held stationary and slowly released by the leaves 34 to allow the ends of the undesired labels to free themselves from the applied label and spring back in position upon the stack, to be taken up by the following cans. Before the can picks up a label a quantity of paste is applied to the outer lower end of the latter by mechanism to be later described. As the label is wrapped about the can, when the latter again begins to revolve, upon being released by the leaves 34, the previously applied paste will securely hold the same to the can and further sealing of the same is effected, after the can leaves the tracks, by the provision of a sealing mat or pad 45 formed of suitable resilient material, preferably of rubber, which extends at substantially the same inclination as the tracks 44, from a point near the rear end of the stack of labels to the discharge end of the machine. The pad 45 is rigidly held in position with the side edges thereof spaced from the sides of the frame, as shown in Fig. 3 of the drawing, so that the end flanges of the can which are of slightly larger diameter than the body of the can, as ordinarily constructed, will not contact with the pad, and the latter may firmly press the label to the body of the can between the said flanges.

In order that the free or outer end of the label which, when applied to the can, extends longitudinally of the same, may be securely pasted at its extreme edge, it is necessary to apply the paste separately to each in-

70

dividual label upon the blank side thereof and at the extreme edge just prior to its application to the rolling can. It is also necessary that the paste be applied only to the uppermost label in order that the labels may not adhere to each other at this end. In order to accomplish these results, a rod 46 extending transversely of the machine is adapted to be coated with paste and to be brought down upon the upper face of the uppermost label to apply a quantity of paste thereto and to be then moved out of the way of the rising label being wrapped about the rolling can. The ends of the transverse paste-applying rod 46 extend through slots 47 formed in guide plates 48 which are detachably secured to the outer faces of the frame members 2, the latter being open at this point. The upper ends of the slots 47 are curved towards the rear of the machine and the ends of the rod 46 are elevated and caused to be drawn rearwardly away from the stack of labels by following said curved slots by means of elevating arms 49 secured, at their rear ends, to the terminals of a transverse rock shaft 50 journaled in the members 2. The arms 49 are provided at their front swinging ends with longitudinal slots 51 which engage the ends of the pasting rod 46 and permit the latter to traverse the curved slots. A bell crank lever 52 is fulcrumed at its angle upon a rock shaft 53 extending across the frame, said bell crank having a lug 54 at the lower end of its front arm to extend beneath the adjacent elevating arm 49 at a point removed from the rock shaft 50 and as the bell crank is rocked forwardly both of the arms 49, and consequently the pasting rod 46, are elevated. In order to actuate the bell crank lever, connection is made, as at 55, to the lower end of the rear arm thereof, with a pull rod 56 which extends forwardly along one side of the machine and is terminally connected to a crank arm 57 attached to one end of the aforesaid rock shaft 41. When the latter is actuated by the trip arm 40 under the pressure of a rolling can, it will be seen that the pasting rod 46 will be brought to the upper extremities of the curved slots 47. At this moment, the rock shaft 53, which is provided with a central, yoke-shaped arm 58 connected at its free end to a transversely-disposed trough 59, has brought the latter up beneath the pasting rod 46 to apply a quantity of paste to the same. In order to supply the trough at each falling movement of the same with a fresh supply of paste, a small tank 60 is supported between the frame members and beneath the rock shaft 53 in position to permit the feeding trough 59 to lower thereinto. The tank 60 is preferably mounted for easy removal from the frame for the purposes of cleansing, by securing the same to a slide 61 in the form of a plate adapted

to slide beneath lugs 62 and having a handle 63.

In order to prevent the inclined stack of labels L from sliding downwardly upon the bed 42 and also in order to maintain the upper end of said stack in a vertical line to 70 allow the can to more readily pick up a single label, a plurality of upstanding guard fingers 64 are supported on the rear end of the bed to support the lower, rear edges of the several labels. When the pasting rod 46 has been 75 brought down upon the rear edge of the uppermost label and starts to withdraw therefrom, the tendency is to draw the label with the same by reason of the paste, and provision has been made to guard against such 80 action by means of a presser bar 65 having its lower face formed into a blunt knife edge to contact with the uppermost label and, by reason of its weight, to hold the stack of labels down upon its support. The presser bar has 85 its ends shaped to freely slide up and down and be guided in vertical slots 66 formed in the aforesaid plates 48, the vertical position of the bar thus depending upon the number of labels in the stack. When the upper label 90 is stripped from the top of the stack by winding around the rolling can, the knife edge of the presser bar serves to remove any excess paste which may be thereon. In placing a new stack of labels in position upon the support or bed 42, the presser bar 65 may be 95 raised and held in an out of the way position, by resting the same upon a shoulder 67 formed in the upper ends of the slots 66.

Since all can labels do not extend entirely 100 from the top to the bottom of the cans when applied, the labels in the use of the present invention must be positioned in proper transverse relation to the sides of the frame at the discharge end of the machine, and for this 105 purpose, guard plates 68 are provided to abut the edges of the labels and maintain the same in perfect alinement to be properly picked up, one at a time, by the cans. The guard plates are of triangular form, their lower edges 110 conforming to the inclination of the bed 42 and being slightly spaced therefrom, while their upper edges are arranged at a slight angle below the tracks 44 to escape the cans as they move rearwardly. Each guard plate 115 is supported upon a pair of sliding bolts 69 rigidly secured to the plates and passing outwardly through apertures in the sections 2 of the frame, each bolt having springs 70 bearing against washers for normally forcing the plates outwardly to abut against set screws 71 which may be used to secure the required nicety of adjustment of the guard plates.

When labels are to be applied to cans of different sizes, it is necessary that labels of different lengths be used, with the result that the can must be allowed to drop over the end 6^a of the tracks 6 and onto the front ends of

the labels at different points relative to the location of the final pasting means. It thus becomes necessary to shift the track members 6 along the upper edges of the frame and for this purpose the flanges 10 of the track members and the supports 11 of the frame are each provided with corresponding teeth or projections 72 which serve to hold the track members in the desired adjustment.

10 When the can has passed the first trip lever 23 a counterbalance weight 73 secured to an arm on the rock shaft 24, together with the weight of the pasting arms 27 will serve to return the parts to their normal positions and 15 to permit a preceding can to pass through the leaves 34 to pick up its label and receive the final pasting.

The removable paste container 13 is preferably formed with inclined front and rear 20 sides and the same is also formed in two compartments, as shown in Fig. 8 of the drawings, the outer compartment providing for conveniently filling the container, the same being located on the outside of the frame and 25 being connected to the main portion by a restricted passageway 74 passing beneath the side of the frame.

It is thought that the description of the 30 operation of the various parts which has been included through the foregoing specification will obviate the necessity for any further explanation thereof.

From the foregoing it will be seen that an 35 improved, relatively simple, compact and efficient means has been provided for automatically applying labels to cans of various sizes, using a minimum amount of paste and preventing the application of more than one label to a can.

40 Obviously the present invention is not restricted to the particular embodiment thereof herein shown and described. Moreover, it is not indispensable that all the features of the invention be used conjointly, since they may 45 be employed advantageously in various combinations and subcombinations.

What is claimed is:

1. A machine for automatically applying labels to cans comprising inclined tracks for 50 the cans to roll upon; means at the upper end of the tracks to cause the passage of a single can at a time; means to apply paste partially around the can; label supporting means intermediate the ends of the machine and having 55 a stack of labels thereon; means for checking the rolling movement of the can and causing same to drop upon the upper end of the uppermost label; means for slowly releasing the can to start rolling again; means for pasting the free, outer edge of the label; and means for finally pressing the entire label against the can.

2. In an automatic can labeling machine; a frame having inclined tracks for the cans to

roll upon; means operable by each can to 65 retard the passage of the following cans down the track; a paste receptacle arranged beneath the tracks; a trip lever arranged in the path of the can; a plurality of paste-applying fingers normally projecting into the paste; 70 gearing connecting the lever to the fingers to elevate the latter into contact with the can when the latter rolls past and deflects the lever; a bed having labels supported thereon midway of the machine; means for causing 75 the can to drop on to the front edge of the uppermost label; means for causing the can to slowly start rolling again after dropping; means for applying paste to the rear edge of the uppermost label; and means for pressing 80 said edge into contact with the can.

3. An automatic can labeling machine comprising a frame having a pair of inclined tracks for cans to roll upon; a cross shaft mounted above the tracks; a central, longitudinal arm extending rearwardly from the shaft normally at an inclination and adapted to be elevated by a rolling can to rock the shaft; lugs extending forwardly from the shaft at an angle to engage and retard the 90 next following can until the first can has passed from beneath the end of the arm; means for applying paste to the rolling can; a bed supporting a stack of labels in the path 95 of the rolling cans; means for causing the can to drop upon and pick up a label; and means for pasting the free edge of the label.

4. An automatic can labeling machine comprising a frame having a pair of inclined tracks for cans to roll upon; a cross shaft mounted above the tracks; a swinging arm on the shaft adapted to be actuated by a rolling can; lugs extending forwardly from the shaft at an angle to engage and retard the next following can until the first can has passed from beneath the end of the arm; means for applying paste to the rolling can; a bed supporting a stack of labels in the path of the rolling cans; means for causing the can to drop upon and pick up a label; and means for pasting 105 the free edge of the label.

5. In a can labeling machine; a frame having upper inclined tracks for the entrance of cans and lower inclined tracks for the discharge of labeled cans, the inclination of the upper tracks being greater than the inclination of the lower tracks, and the lower end of the entrance tracks being located above the higher end of the discharge tracks; an inclined bed arranged at the juncture between the tracks and supporting a stack of labels thereon; can-stopping means near the lower ends of the upper tracks to check the cans and cause same to drop vertically upon the upper ends of the labels; means mounted between the upper tracks for applying paste to the cans to pick up the uppermost label; means mounted between the lower tracks for apply-

ing paste to the free edge of said label; and means for pressing the surrounding label to the can.

6. In a can labeling machine; upper and lower inclined tracks for cans to roll upon; a stop located at the lower ends of the upper tracks and operable by the can to apply paste to the same and means to retard the next following can; a stop located at the lower ends of the upper tracks to cause each can to fall vertically therefrom; an inclined bed having a stack of labels thereon with their upper ends elevated above the lower tracks to receive the falling can; leaves mounted in the lower end of the upper track section and operable by the next following can to slowly release the first can to pick up only the top label; means located at the lower end of the bed for applying paste on the lower edge of each label; and means mounted between the upper tracks to be actuated by the cans for operating the label pasting means.

7. In a can labeling machine; upper and lower inclined tracks; means arranged between the upper tracks to be actuated by cans rolling upon the tracks for applying paste to the can; an inclined bed having a stack of labels located beneath the lower ends of the upper tracks; means for stopping the can after it passes the ends of the upper tracks to cause the can to fall upon the upper edge of the top label; opposite leaves operable by the said paste applying means to check the can after falling and for causing the can to slowly start rolling again; a paste receptacle at the lower end of the bed; a paste-applying bar arranged transversely of the machine to contact with the lower edge of each label; means for lifting the bar from the label; and means for applying paste to the bar when lifted.

8. In an automatic can labeling machine; a frame having inclined tracks for the cans to roll upon; means operable by each can to retard the passage of the following cans down the track; a paste receptacle arranged beneath the tracks; a trip lever arranged in the path of the can; means for applying spaced lines of paste partially around the cans; gearing connecting the lever to the fingers to elevate the latter into contact with the can when the latter rolls past and deflects the lever; a bed having labels supported thereon midway of the machine; means for causing the can to drop on to the front edge of the uppermost label; means for causing the can to slowly start rolling again after dropping; means for applying paste to the rear edge of the uppermost label; and means for pressing said edge into contact with the can.

9. In a can labeling machine; upper, inclined entrance tracks for cans; means for causing but one can to enter at a time; means for applying paste to each can; lower, inclined discharge tracks arranged below the entrance tracks; an inclined bed having a

stack of labels thereon; means for causing each can to drop from the upper tracks on to the upper edge of the upper label; means for causing the can to slowly start rolling again to pick up the upper label; a transverse pasting bar adapted to apply paste along the lower edge of the upper label; means for removing the bar when the label is picked up; means for removing excess paste from the edge of the label; and a rubber pad for finally pressing the label around the can.

10. In a can labeling machine; upper, inclined entrance tracks for cans; means for but one can to enter at a time; means for applying paste to each can; lower, inclined discharge tracks arranged below the entrance tracks; an inclined bed having a stack of labels thereon; means for causing each can to drop from the upper tracks on the upper edge of the upper label; means for causing the can to slowly start rolling again to pick up the upper label; guide plates secured to the sides of the lower track members and having spaced vertical slots, the rear slots having rearwardly curved upper ends; a transverse pasting rod terminally mounted to slide in the rear slots; crank arms connected to the ends of the bar; and a trip lever mounted between the upper tracks and connected to the crank arms to be actuated by a following can to elevate the said paste bar when a can lifts the top label.

11. In a can labeling machine; upper, inclined entrance tracks for cans; means for causing but one can to enter at a time; means for applying paste to each can; lower, inclined discharge tracks arranged below the entrance tracks; an inclined bed having a stack of labels thereon; means for causing each can to drop from the upper tracks on the upper edge of the upper label; means for causing the can to slowly start rolling again to pick up the upper label; guide plates secured to the sides of the lower track members and having spaced vertical slots, the rear slots having rearwardly curved upper ends; a transverse pasting rod terminally mounted to slide in the rear slots; a transverse presser and wiper bar mounted to slide in the front slots; crank arms for elevating the rod; a rock shaft for actuating the cranks; a paste tank at the lower end of the bed; a movable trough mounted to drop into the paste; and means, operable by the rolling cans, to raise the trough and apply paste to the rod when the latter is elevated by the same means.

12. A can labeling machine comprising, in combination, an inclined way for rolling cans; means for releasing cans, one at a time, to roll down said way; means for applying paste to the cans while they are rolling; a bed supporting a stack of labels so arranged that the cans fall on the labels and pick up one at a time; means for automatically applying paste to one edge of the labels; and means to wipe

the edge as the label is wrapped around the can.

13. A can labeling machine comprising, in combination, an inclined way for rolling cans; means for releasing cans, one at a time, to roll down said way; means for applying paste to the cans while they are rolling; a bed supporting a stack of labels so arranged that the cans fall on the labels and pick up one at a time; means for automatically applying paste to one edge of the labels; and a blunt edge wiper arranged transversely of the machine to loosely bear upon the uppermost label and scrape excess paste from the edge thereof as the label is picked up by the rolling can.

14. A can labeling machine comprising, in combination, an inclined way for rolling cans; means for releasing cans, one at a time, to roll down said way; means for applying paste to the cans while they are rolling; an inclined bed having a stack of labels thereon mounted midway of the run for cans to fall upon; means for supporting the labels with their front edges in vertical alignment; means for applying a narrow strip of paste to the rear edges of the labels; means for scraping the excess paste therefrom; and triangular guage plates adjustably mounted at each side of the bed to position the labels laterally to receive the falling can.

15. A can labeling machine comprising, in combination, a frame; an inclined runway for rolling cans mounted upon the frame, said runway having an entrance portion and a

discharge portion, the entrance portion terminating above the upper end of the discharge portion to cause the cans to fall; means for supporting a stack of labels in inclined position below the falling cans; and means for longitudinally shifting the position of the entrance portion of the runway relative to the discharge portion to cause the can to properly fall upon the upper edge of the upper label.

16. A can labeling machine comprising, in combination, a frame; upper and lower inclined runways mounted longitudinally upon the frame, the lower end of the upper runway terminating midway of the frame and above the upper end of the lower runway; means operable by the cans to admit one can at a time, and to apply paste thereto while rolling along the upper runways; means for causing the cans to fall vertically from the end of the upper runway; an inclined label bed beneath the said end and having a stack of labels thereon; means for positioning the labels transversely; means for causing the can to start slowly to pick up only the upper label; means for applying a narrow band of paste along the lower edge of said label; means for removing excess paste; and a resilient platform to press the label to the can as the latter leaves the lower end of the lower runway.

In testimony, that I claim the foregoing as my own, I have hereto affixed my signature.

LERROY BIGGS.
